SOUND SIGNAL

Robert M. Critchfield, Anderson, Ind., assignor, by mesne assignments, to General Motors Corporation, Detroit, Mich., a corporation of Delaware

Application May 15, 1929, Serial No. 363,183

5 Claims. (Cl. 177—7)

This invention relates to improvements in sound signalling devices and is particularly adaptable to that class of sound signal for use on motor driven vehicles.

5 It is one of the objects of the present invention to provide a sounding signal or horn of simple structure and design, and which may be produced cheaply and with a minimum expenditure of labor.

10 Another object is to provide a horn or sound signal that will give an attractive warning signal, that may be distinctly heard at some distance and above the usual din of city traffic.

Another object of this invention is to provide 15 a sound signal of attractive design, and one which will be more consistent with present day automotive engineering, yet adequately perform the function for which it is intended.

Further objects and advantages of the present 20 invention will be apparent from the following description, reference being had to the accompanying drawing wherein a preferred embodiment of one form of the present invention is clearly shown.

25 In the drawing:

Fig. 1 is a rear view of my improved sound signal with parts shown in half section for clearness of illustration.

Fig. 2 is a section through my sound signal device substantially as indicated by the line and arrows 2—2 of Fig. 1.

Fig. 3 is a front view of my sound signal, and

Fig. 4 is a sectional view similar to Fig. 2, but of a modified form.

35 Referring to the drawing the numeral 20 designates a base providing a main mounting platform 21 upon which is supported the operating mechanism of the horn, and the mounting platform is apertured for reception of a magnet motor, the metal punched out of the bottom to form the aperture being bent up to provide a bracket 22 having a portion 23 parallel with but spaced from the main mounting platform 21. The base 21 is provided with an outwardly extending flange 25

40 having a plurality of apertures for receiving screws 26 which pass through apertures in a flange 27 of a sounding board or clamping ring 28, to secure said sounding board to the base. A diaphragm 29 is interposed between the flanges 25 and 27 of the base and sounding board respectively and is clamped therebetween by means of screws 26, lockwashers 30 and nuts or spacers 31, thus providing a yieldable partition between the base and the sounding board.

45 Upon the parallel portion 23 of the bracket 22

there is secured one end of a blade spring 32 which extends toward the axis of the base parallel with the main mounting frame 21. The contacts of the interrupter mechanism or circuit controller are insulatingly mounted upon this portion 23 of the bracket 22. A resilient plate 33 has a foot portion adapted to be secured insulatingly to the bracket 22, and the free end of said plate is provided with a movable contact element 34 which cooperates with a stationary contact element 35 supported by a contact arm 36 insulatingly secured to the bracket 23 by screws 37. By reference to Fig. 2 it will be clearly seen how the screws 37 are assembled with a washer 38, a non-conducting washer 39, bracket 36, nonconducting 10 bushing 40, nonconducting washers 41, contact spring 33, spacers 42, blade spring 32 and finally the bracket 23. The contact supporting elements 33 and 36 are provided with the suitable leads 43 and 44 which ultimately combine into the common cable 45 which communicates with an appropriate switch and energy source.

An angular bracket 46 is secured to the free end of the blade spring 32 and has an adjustable screw 46a supported at its free end and is locked 25 in the adjusted position by a lock nut 47, said screw being adapted to engage the member 33 carrying the movable contact 34 through a non-conducting wafer 48 interposed therebetween. A rod or armature shaft 50 is secured to the free 30 end of the blade spring 32 and extends toward the diaphragm 29, being secured thereto by means of clamping collars 51 and 52 pressed against opposite sides of the diaphragm by means of a nut 53, provided at the end of the rod 50, which nut 35 also holds a tone modifying disc 54 in position on the rod and in front of the diaphragm 29, a suitable spacer 54a being inserted between the disc and clamping collar 52. An armature 55 is carried on the rod 50 adjacent the free end of 40 the spring 32, said armature being maintained in normal position by the spring 32 and the diaphragm 29.

The armature 55 is reciprocated by means of an electromagnet or magnetic motor, comprising 45 a field frame 60 which is supported on the mounting platform 21 in any desirable manner. The field frame and the armature may comprise a plurality of magnetic plates riveted together as is well known to those schooled in the art, and the field frame may be grooved as at 62 and 63 for receiving a field winding 64. The central portion of the magnetic frame is bored at 65, within which is disposed the armature shaft 50 of the magnetic motor, the aperture being sufficiently greater in 55

diameter than the shaft as to be out of contact therewith at all times.

In the preferred form of my invention the sounding board 28 is substantially cup shaped, or 5 of the cross section generally exhibited in Fig. 2, and the bowl portion thereof is apertured at 70 which leaves a plateau 71 of metal substantially parallel with and spaced from the diaphragm 29 and tone modifying disc 54. This defines a tone 10 chamber 72, within which is disposed the tone modifying disc 54, and, which it may be said is defined by the tone producing elements. At a central portion of the sounding board 28, an adjusting screw 13 and locking nut 14 are provided 15 so as to be substantially coaxial with the armature shaft 50 hereinbefore described. This adjusting screw provides a means of limiting the approach or defines the air gap between the armatures 55 and the field frame 60, and also operates 20 as an anvil upon which the hammer end 75 of the armature shaft 50 may operate.

In a modified form of the device, or that form illustrated in Fig. 4, the sounding board 28a conforms only to an annular flange or rib of the 25 clamping ring 21, the main portion of the sounding board or plateau being entirely omitted. However, in each instance the tone modifying disc 54 has free air access to the open end or bell of the sound signal as will presently appear.

30 The structure thus far described whether it be of the preferred or the modified form, is mounted within a projector or sound reflector as clearly illustrated in the drawing, and so that the sound producing elements are grouped substantially at 35 or near the focal point of the reflector. The reflector is indicated as at 80 and is preferably of parabolic form, the bell thereof terminating in a rolled edge 81, and is provided at specified points with denticulations 82 apertured to receive attaching 40 screws 83 received by the aforesaid nuts or spacers 31. In order to permit the reflector 80 to vibrate at its own fundamental frequency or 45 function most efficiently, the denticulations and attaching screws 83 are located substantially at 50 nodal points in the said reflector, so that the ultimate sound signal produced will be a combination of frequencies produced by all of the above specified tone elements superimposed upon the fundamental tone of the reflector itself.

55 For attaching the sound signal to a part of the vehicle an attaching bracket 85 is provided with offset ears 86 which may be secured to the horn assembly by two of the adjacent attaching screws 83 passing therethrough and into the spacers 31, as illustrated. This bracket provides for mounting the sound signal upon the cross rod or other convenient part of the automotive vehicle. To protect the magnet motor and also to insure that the frequencies produced by the tone elements will 60 be imposed upon the reflector 80, the driving unit or power plant of the horn is provided with the motor housing 90 fitting closely about the unit and provided with the flanged ears 91 apertured to receive attaching screws 92 driven therethrough 65 and into the flange 25 of base 20 as indicated in Figs. 2 and 3. A gasket 93 being inserted between the motor housing and base plate making a tight joint and reducing the noise.

70 It will be noted from the above description that the sound signal embraces a reflector and a tone producing unit grouped at or near the focal point of the reflector so as to make for the greatest efficiency of the device, and that the motor mechanism is entirely enclosed and protected 75 from dust and moisture. It will be also noticed

that the sounding elements of the device face the reflector and are in such position or relation therewith as to give the greatest amplitude of air movement between the reflector and driving unit thus contributing to produce a loud and piercing signal. 5

In the operation of this sound signal the electrical energy is properly transmitted to the driving unit by way of the conductor 45, which driving unit causes the diaphragm 29 to vibrate at its set frequency, which also causes the tone modifying disc 54 to take up its vibratory movement partly due to the operation of the driving unit and partly due to the sympathy it has for the vibrating diaphragm 29. These elements when actuated pulsate the air content of the tone chamber 72 driving the air through the apertures 70 of the sounding board so that the vibrations strike upon and are thrown back by the reflector 80 through the substantially annular channel or 20 throat 95 between the reflector and the edge of the driving unit. The sounding board 28 adds to this sound of combined frequencies a distinct tone of its own part of which is contributed to by the hammering of the armature shaft 50 upon the anvil 73 and part of which is due to its sympathetic response to the frequency of the diaphragm and disc. These sound frequencies when imposed upon and reflected by the member 80, and intermingled with the fundamental frequencies thereof produce a sound signal of striking quality that is very desirable in the present age of automotive industry. The ultimate product of such a sound signalling device may be characterized as one of low fundamental pitch 35 superimposed with higher frequencies of contrasting color, intermingled with many over tones of substantial timbre. 30

In the modified form, the operation is essentially the same, in fact is the same except for the 40 function of the sounding board. The sound product is noticeably different in timbre from that of the preferred form, for here the sound product is the result of the combined frequencies of the diaphragm 29 and the tone modifying disc 45 54 being directly reflected and intermingled with the fundamental of the reflector 80. Here the sounding board 28a acts more as a stiffening ring or clamping collar for the diaphragm 29 and adds little to the tone value of the signal device. The 50 sound signal of this device is noticeably shriller and of less timbre than that of the sound signal of the preferred form.

While the form of embodiment of the present invention as herein disclosed, constitutes a preferred form, it is to be understood that other forms might be adopted, all coming within the scope of the claims which follow.

What is claimed is as follows:

1. A sound signal device comprising in combination, a resonating reflector, a magnetic motor, means supporting the motor within said reflector, and tone producing elements near the focal point of said reflector, and means driven by said magnetic motor for actuating said elements, said reflector and magnetic motor being connected substantially at nodal points of said reflector. 65

2. A sound signal device comprising in combination, a horn projector including a cupped resonating reflector, a diaphragm, a resonating disc, 70 means mounting the diaphragm within the said reflector, a base, driving means supported from the base for vibrating the diaphragm and disc, a sounding board secured to the diaphragm edge, the driving means having a part periodically en- 75

gageable with the sounding board during diaphragm vibration, the diaphragm and sounding board enclosing the disc so as to form a tone chamber, and means spacing the edges of the 5 sounding board and diaphragm from the reflector to allow free passage of the reflected sound vibrations therebetween.

3. A sound signal device comprising in combination, a base, a resonating reflector, a diaphragm 10 and sounding board, means at the edges of the diaphragm and sounding board securing them to the base and spacing them from the reflector, a motor, means connecting the motor with said diaphragm and for actuating said sounding 15 board, said connecting means extending through said diaphragm and cooperating with a part on said sounding board to actuate the sounding board.

4. A sound signal device comprising in combination, a resonating reflector, a motor, means supporting the motor from said reflector, tone 20

producing elements comprising a diaphragm and a disc, means driven by said motor for actuating said elements, said supporting means positioning the tone producing elements between the motor and the reflector, and said securing means being located at points substantially in the nodal region of said reflector and adapted to maintain the motor and reflector in spaced relation. 5

5. A sound signal device comprising in combination, a resonating reflector, a motor, tone producing elements, comprising a diaphragm, and tone modifying disc secured thereto, a sounding board having an edge portion secured to the diaphragm and cupped to enclose said disc, means driven by said motor for actuating said elements, and for striking said sounding board, and means for mounting said motor and tone producing elements at points substantially in the nodal region of said reflector so as to locate the tone producing elements between said motor and said reflector. 10 15
